UNITED STATES PATENT OFFICE

96,302

DESIGN FOR AN OIL BURNER

Bernard H. Dow, Baltimore, Md., assignor to May
Oil Burner Corporation, a corporation of
Maryland

Application May 24, 1935, Serial No. 57,010

Term of patent 7 years

To all whom it may concern:

Be it known that I, Bernard H. Dow, a citizen of the United States and residing in the city of Baltimore, in the State of Maryland, have invented a new, original, and ornamental Design for Oil Burners, of which the following is a specification, reference being had to the accompanying drawings, forming a part thereof.

Figure 1 is a plan view of the oil burner showing my new design.

Figure 2 is a side view of the oil burner shown in Figure 1.

Figure 3 is a front quartering view in perspective of the oil burner shown in Figures 1 and 2.

I claim:

The ornamental design for an oil burner as shown.

In testimony whereof, I affix my signature.

BERNARD H. DOW.
